UNITED STATES PATENT OFFICE

151,823

DESIGN FOR A SANITARY JUICE
COLLECTOR

Oscar E. Hammers, Chicago, Ill.

Application December 27, 1946, Serial No. 135,794

Term of patent 14 years

(Cl. D44—10)

To all whom it may concern:

Be it known that I, Oscar E. Hammers, a citizen of the United States, residing at 7229 Summerdale Avenue, in the city of Chicago, county of Cook, and State of Illinois, have invented a new, original, and ornamental Design for a Sanitary Juice Collector, of which the following is a specification, reference being had to the accompanying drawings, forming a part thereof.

Fig. 1 is a side elevational view of the sanitary juice collector showing my new design.

Fig. 2 is a view taken from the top of the sanitary juice collector.

Fig. 3 is an end view of the sanitary juice collector, and

Fig. 4 is a view taken from the bottom of the sanitary juice collector.

I claim:

The ornamental design for a sanitary juice collector, as shown.

OSCAR E. HAMMERS.
